UNITED STATES PATENT OFFICE.

ROY D. MAILEY, OF EAST ORANGE, NEW JERSEY, ASSIGNOR TO COOPER-HEWITT ELECTRIC COMPANY, A CORPORATION OF NEW JERSEY.

MERCURY SWITCH.

Application filed October 27, 1923. Serial No. 671,104.

My present invention relates to switches for electric circuits in which movements of the liquid mercury in said switches achieve the making and breaking of the electric conducting path therethrough. It particularly relates to such a switch in which provision is made for the automatic opening thereof at normal or at excessive temperatures when the switch is used with heating apparatus or apparatus which becomes or may become heated during use and availing of the temperature of the heating device to cause the transfer of the liquid mercury from between the terminals of the switch to open the circuit therethrough.

Electric heating apparatus especially of the domestic types are a recognized source of fire hazard and this is especially true in the case of electrically heated flat irons although my invention is applicable to heating or heated apparatus in the arts generally. Many devices are known whose object it is to eliminate or circumvent this hazard but heretofore results therewith have not been entirely satisfactory.

It is the object of my invention to provide a switch for electrical heating apparatus which will automatically open the circuit therethrough when such devices are left standing with the current turned on through the switch.

It is another object of my invention to provide such a thermostatic switch which is simple of operation, fool proof, and simple of construction.

It is another object of my invention to provide such a switch which will automatically open when the device in which it is used is out of its normal position.

It is another object of my invention to provide an electric flat iron switch which will continue to function to open at normal or excessive temperatures, which is automatically closed by the motion of the iron in its use, but will function to open and remain open if left standing in the operating position.

Fig. 1 is an elevation view of my switch in section showing it in its normal position and closed.

Fig. 2 is an elevation view of my switch in section showing a part of the mercury as having moved from the circuit making position whereby the switch is opened.

Fig. 3 is a view in section of my switch tilted in the plane of its width and showing opening operation of switch in this position.

Fig. 4 is a view in section of my switch tilted sidewise and showing opening operation of switch in this position.

Fig. 5 is a vertical sectional view of another form of my invention.

Fig. 6 is a vertical sectional view of this latter form of my invention showing the switch inverted and the electric path therethrough disrupted.

Fig. 7 is a vertical sectional view of the third form of my invention.

Fig. 8 is a vertical sectional view in this third form showing the operation thereof through movements of the mercury therein.

Fig. 9 is an inverted sectional view of this third form showing the disruption of the electric path from the movements of the mercury therein as a result of this inversion.

Fig. 10 is a vertical sectional view electrically heating flat iron to which the switch of my invention is applied.

Fig. 11 is an elevation view of a switch embodying my invention in which the electrode leads are sheathed in surrounding tubes extending below the lower extremities of the electrodes and providing spaces at the terminals for the making and breaking of arcs between the electrodes and the mercury body.

Fig. 12 is an elevation of a U-tube switch having mercury therein, electrodes in the legs of the U, and a condensing chamber for each of the legs near its top.

Fig. 13 is a plan view of the switch of Figure 12.

Fig. 14 is a side elevation view of the switch of Figure 12.

The device of my invention comprises a body of mercury, or of some other movable and vaporizable substance electrically conductive in the useable state, which is enclosed in the chamber of a vitreous envelope

of such material as glass. Through the walls of the envelope and in contact with the said body of mercury, for example, are sealed electrical conductors which on their outer ends are suitably connected to electric mains and heating apparatus. Connecting with the said chamber near its top is a condensing chamber for the condensation and collection therein of vaporized mercury or the like passing thereto from the main chamber. Means is provided for preventing the flow of the condensed mercury back into the main chamber. Such means as described below and shown in the drawings are embodied in a lower floor or boundary for such condensing chamber which recedes from the main chamber to form with the other walls of said chamber a liquid collecting pocket. Another embodiment shown and described is a raised rim or ridge at the confluence of the two chambers which rim or ridge serves as a dam to hold back and collect condensed liquid in the condensing chamber. Such recession of the floor or such raising of a rim is of such degree as to permit, for instance in the use of my switch in an electric heated flat iron, of a constant and continuous return of the mercury or other liquid collected in the condensing chamber through the normal movement of the iron in its use for ironing. When the iron is in use and the switch in almost constant motion the condensed mercury is continually returned to the main body and the switch left closed. Any cessation of motion will mean the accumulation of mercury in the condensing chamber and a continuation thereof will result in the opening of the switch, and the discontinuing of current supply to the heating element, and the cooling of the iron. Further, some forms of the device of my invention provide for the opening of the switch either by evaporation and condensation or by the flowing of the mercury therein from the circuit making position in any position out of the normal in which switch may be placed either accidentally or intentionally.

In the switch of my invention I use mercury within a sealed envelope having electrodes sealed through the walls thereof and a subchamber into which the mercury moves by distillation and condenses. This subchamber is so constructed with respect to the main envelope or chamber that the mercury which distills thereto and condenses therein can be easily and quickly moved back to the main chamber by a simple movement of the switch or of the apparatus in which the switch is installed or by its normal movement in the use of the apparatus in which it is installed.

As an example I shall describe the use of the switch of my invention in connection with an electrically heated flat iron.

65 In the drawings is shown an envelope 1 as

of glass having a condensing subchamber near its top and the level of the bottom boundary of which lowers away from the main chamber. Through the walls of the envelope 1 are sealed electrodes 3 and 4 which in the normal position and condition of the switch are connected by the body of mercury, 2 within said envelope. Under normal operating or excessive temperature, a part of the body of mercury 2 will be distilled therefrom passing into the subchamber or pocket 5 where it will condense and accumulate as shown in Figures 2, 3, 4, 5 and 8 of the drawings. This distillation and accumulation will continue while such normal or excessive temperature is maintained when the switch is at rest until sufficient mercury passes from the main body 2 to disrupt the electrical conducting path between electrodes 3 and 4 as shown in Figures 2, 3, 4 and 8.

Figure 3 which shows the switch tilted in the plane of the switch and in the direction of the pocket 5, also shows the movement of mercury therein by distillation and condensation into said pocket 5 to open the circuit between the terminals of the switch. Also should the switch be tilted sidewise (see Figure 4) the disruption of the electric circuit therethrough will still occur, the capacity of said pocket 5 being such as to hold sufficient mercury to result in the opening of the circuit through the switch. In Figures 5 and 6 I have shown the electrodes 3 and 4 which extend downwardly from the top of the envelope to the mercury contained therein, as in the form shown in Figure 1, as being coated with the material of the envelope body to within a short distance of their inner ends or with some other suitable material. In this form upon change of position of the switch from a position in which pocket 5 will hold and accumulate mercury, the mercury will flow away from one or both of the electrodes 3 and 4 to disrupt the electrical conducting path therebetween. An example of the extreme position of this sort is shown in Figure 6 where a switch is inverted and mercury has flowed completely away from electrodes 3 and 4. Between this extreme position and the normal position of the switch this form of my invention is designed to function to open the circuit therethrough either by the flowing of the mercury away from the electrodes on the assumption of such position to disrupt the electrical conducting path therebetween or to evaporate, condense and accumulate mercury in said pocket 5 when the switch is subjected to normal or excessive temperature whereby the electrical path through said switch is opened.

In Figures 7, 8 and 9 is depicted a third form of my invention which operates in the same manner as that of the second form

which is shown in Figures 5 and 6. In this third form electrodes 8 and 9 thereof are sealed in through the bottom of the envelope 1 and are coated within a short distance of 5 their inner ends by the material of the envelope body and continuous therewith or by some other suitable material. It is clear in this form of my invention that the electrodes can be sealed into the envelope body 10 at any desired position through the walls thereof.

In Figure 10 is shown flat iron 10 into the body of which is inserted the lower part of the switch envelope 1 the said lower 15 part situated near the heating element 11 of the iron and showing the subchamber or pocket 5 as situated outside and away from said heating element. Said lower boundary of the subchamber or pocket 5 is approximately 20 a plane or is of such shape that when the switch is sufficiently tilted in the direction away from said pocket that any mercury therein will flow back into the main chamber 1. In this position the main body of 25 mercury 2 is subjected to the temperature of the iron while the subchamber or pocket 5 remains always at a much lower temperature when the iron is heated and at a temperature at which any mercury distilled therefrom 30 will condense and accumulate therein.

In the operation of the first form of the device of my invention, using the electrical heated flat iron application as an example, when the flat iron is in its normal position 35 and current turned thereon a conducting path will continue therethrough until a temperature is reached such that will cause the distillation of mercury vapor from the mercury body 2 and the passing thereof to pocket 5 and the condensation thereof in said 40 pocket where it will accumulate in body 6. This distillation, accumulation, and condensation will continue while such temperature prevails until the conducting path between electrodes 3 and 4 is disrupted and the 45 current through said heating element 11 is discontinued whereupon the temperature in said iron lowers and any danger of fire hazard through it is averted. To return the 50 mercury 6 to the main body of mercury 2 the iron is simply shaken or tilted to cause said mercury 6 to flow back to the body 2.

In Figure 11 is shown a form of my invention in which the electrodes 3 and 4 are sealed 55 through the top of the envelope 1 of the switch, each of said electrodes being surrounded by the glass tubes 12 which extend beyond the inner ends of the electrodes to provide restricted spaces about said ends and which serve to a degree to quench or dissipate any arcing that takes place on the movement of the mercury away from such ends. About midway between the ends of 60 such tubes 12 are the holes 13 which serve to equalize vapor pressures throughout said

tubes 12 and the interior of envelope 1. The rim 14 between chamber and condensing chamber 5 is of such height as to hold sufficient mercury on the substantially horizontal floor 15 of chamber 5 to result in the 70 opening of the circuit between electrodes 3 and 4.

In Figures 12, 13, and 14 is shown the switch body 16 which is substantially a sealed U-tube to the upper part of the legs 17 75 of which connect the condensing chamber 18, 19. The electrodes 3 and 4 are sealed in through the tops of the legs 17 and extend into the mercury body 2. In this form of my invention upon the evaporation of 80 mercury, from body 2 and its condensation and any arcing which might occur between the electrodes and the mercury in cases where the current therethrough is heavy enough to sustain an arc the carrying on of 85 the arc to the electrodes themselves is prevented by the length of the path presented between the electrodes.

When desired, the switches may be filled 90 with suitable gas such as hydrogen, nitrogen, etc. for dissipating the heat at the instant of breaking of the circuit and to serve also in quenching any arc which would tend to form.

I claim:

1. In an electric switch in which current is made and broken by the movement of liquid forming a part of the electric circuit, in combination, a sealed envelope having a main chamber and a condensing chamber, a conducting liquid in said main chamber, and electrodes sealed through the walls of the envelope and extending into said liquid. 100

2. In a switch, in combination, a sealed envelope having a main chamber and a condensing chamber, vaporizable material in said main chamber, and electrodes sealed through the walls of said envelope and connecting electrically with said vaporizable material. 105

3. In a mercury switch, in combination, a sealed envelope comprising a main chamber and a condensing chamber connecting therewith, and electrodes sealed through the walls of said envelope and connecting electrically 110 with said mercury, said condensing chamber forming a pocket to accumulate and hold mercury condensed therein.

4. In a mercury switch, in combination, a sealed envelope comprising a main chamber and a condensing chamber connecting therewith, a body of mercury in the bottom of said main chamber, electrodes sealed through the walls of said envelope and extending into said body of mercury, and a vitreous coating 120 on said electrodes extending from the point of sealing-in to short distance of the ends of the electrodes. 125

5. In a mercury switch, in combination, a sealed envelope comprising a main chamber 130

and a condensing chamber, a body of mercury in said main chamber, electrodes sealed through the walls of said envelope and extending into said body of mercury,
5 and insulating coatings of vitreous material on said electrodes fused to the wall of the envelope at the seal-ins and extending to within a short distance of the inner ends of said electrodes, the lower floor of said condensing chamber receding slightly downwardly away ¹⁰ from the confluence of the two said chambers.

Signed at Hoboken in the county of Hudson and State of New Jersey this 26th day of October A. D. 1923.

ROY D. MAILEY.
